UNITED STATES PATENT OFFICE.

THOMAS HENRY ALEXANDER BROWN, OF HEIDELBERG, TRANSVAAL, SOUTH AFRICA.

LOCKING LAMP-SOCKET.

1,259,482.

Specification of Letters Patent. Patented Mar. 19, 1918.

Application filed October 27, 1915. Serial No. 58,261.

To all whom it may concern:

Be it known that I, THOMAS HENRY ALEXANDER BROWN, subject of the King of Great Britain, residing at Power Station, municipality of Heidelberg, Transvaal Province of the Union of South Africa, have invented 5 certain new and useful Improvements in Locking Lamp-Sockets, of which the following is a specification.

10 The purpose of the present invention is to provide simple and effective means for locking an electric lamp bulb in its socket.

In the accompanying drawings,

Figure I shows the invention applied to 15 the ordinary bayonet slot socket; parts being broken away.

Fig. II is a section on A—A Fig. I looking upward.

Fig. III is a similar view to Fig. II but 20 showing the lamp being released.

1 indicates the common lamp socket having an external screw thread 2 and bayonet slots 3, into which are engaged the radially extending pins 4 of the lamp cap 5. On the 25 socket are latches formed of arcuate flat springs 6 secured at one end 7 to the socket. Said springs are formed with holes 8 opposite the inner ends 9 of the bayonet slots, so that the pins 4, when passed into said ends 9 30 of the slots, also pass into the holes 8 and are thereby locked in place.

The free ends 10 of the springs are directed anti-clockwise, i. e. against the incoming movement of the pins 4, and are curved outwardly as shown. The edges 11 of the 35 springs extend somewhat below the lower end 12 of the socket. Thus upon pushing in the lamp cap until it is stopped by its pins 4 and then rotating it clockwise, as usual, the pins 4 travel around the lower end 12 of the socket (first possibly traveling around the exposed lower edges 11 of the springs) until they pass under the free ends 10 of the springs and continue their movement into 40 the bayonet slots 3, so raising the springs which afterward drop over them.

13 is a barrel rotatably mounted on the socket as by screwing it onto the threaded part 2 thereof. The lower end of the barrel 50 is formed with an inward flange 14 which covers in the springs 7. Said flange is slotted diametrically at 15 to admit the lamp cap pins 4. The upper end 16 of the barrel may be beveled to carry the lamp shade 17. 55 In the side of the barrel are formed dia-

metrally opposite holes 18 for the insertion of the releasing key.

The preferred form of releasing key consists of two arms 19 hinged together at 20 and of arcuate shape to fit around the barrel 60 13. A spring 21 tends to close said arms together; and grips 22 are provided by which the device may be held between the finger and thumb (as shown in Fig. II) and by pressing on which the arms may be opened 65 against the pressure of the springs 21. Each arm has an inwardly directed peg 23 of such length that when inserted through the holes 18 it extends approximately to the surface of the socket. When the pegs are so inserted, 70 (the barrel having if necessary been screwed away from the shade 17 or the lamp cap 5 to enable it to rotate freely) relative rotation is brought about between the lamp and socket on the one hand and the barrel and 75 key on the other hand such that the lamp turns anti-clockwise with respect to the barrel.

The free ends of the springs are thereby brought up against the pegs (Fig. III) and 80 are raised by them so releasing the lamp pins 4 and allowing the removal of the lamp by continuation of its relative movement. The holes 18 are so positioned relatively to the slots 15 that when the lamp is unlocked said 85 slots 15 are opposite the open ends of the bayonet slots 3,—as seen in Fig. III,—so that the lamp can be drawn straight away from the bayonet slots.

I claim—

1. The combination with a lamp socket of an automatically closing latch arranged to lock onto a pin on the lamp cap when the lamp is in position in the socket, and, of 90 itself, lock the lamp in place.

2. The combination with a lamp socket of an automatically closing latch provided with an aperture into which a pin on the lamp cap is adapted to protrude when the lamp is in position in the socket.

3. The combination with a lamp socket of a spring latch provided with an aperture into which a pin on the lamp cap is adapted to automatically protrude when the lamp is in position in the socket.

4. The combination of a lamp socket provided with a slot, an automatic spring actuated locking member having an aperture registering with the slot in the socket, and a lamp cap having a pin adapted to travel in 110

- the slot of the socket and enter the aperture in the automatic locking member for the purpose of locking the lamp cap against movement in the socket until the automatic locking member is withdrawn from the pin.
5. The combination with a slotted lamp socket, of an automatic locking latch mounted thereon, a lamp cap provided with a pin adapted to enter the slot in the socket and be 10 automatically locked in said slot by the latch, and a barrel mounted for rotation on the socket and having an aperture through which a finger may protrude, whereby the rotation of the barrel, with the finger in place causes 15 said finger to engage with, and retract the locking latch and release the pin.
6. The combination with a slotted lamp socket, of an automatic locking latch mounted thereon, a lamp cap provided with a pin 20 adapted to enter the slot in the socket and be automatically locked in said slot by the latch, a barrel mounted for rotation on the socket and having an aperture through which a finger may protrude, whereby the 25 rotation of the barrel, with the finger in place causes said finger to engage with, and retract the locking latch and release the pin, and an inturned flange at the end of the barrel to preclude tampering with the locking latch.
7. The combination with a slotted lamp socket of a lamp cap provided with a pin adapted to enter the slot of the socket, and a spring adapted to engage with and lock the 35 pin in the slot, said spring being maintained in locked position entirely by its own resiliency.
8. The combination with a slotted lamp socket, of a lamp cap provided with a pin 40 adapted to enter the slot of the socket, and a locking member adapted, of itself, and

without the employment of extraneous means, to engage with and securely lock the pin of the cap in the slot of the socket.

9. The combination with a lamp socket of 45 an automatically closing lamp locking latch, a member movable on the socket and inclosing the latch and perforated for the insertion through it of a latch releasing means.

10. The combination with a lamp socket 50 of an automatically closing lamp locking latch, and a barrel rotatable on the socket and having a hole so placed that a peg inserted through it releasingly engages the latch upon rotation of the barrel.

11. The combination with a lamp socket, of lamp locking means and a barrel rotatable on the socket and having an end flange which closes in the end of the socket.

12. The combination with a lamp socket 55 adapted to receive a lamp cap with radial pins, of a spring perforated to pass over and automatically lock onto a lamp pin and adapted to be lifted by a lamp pin upon inward movement of a lamp.

13. The combination with a lamp socket adapted to receive a lamp cap provided with a radial pin, of an arcuate lamp locking spring mounted on a socket and having its free end directed oppositely to the direction 70 of the insertion of the lamp, which spring is provided with an aperture adapted to automatically receive the lamp pin and lock the lamp cap against the removal from the socket.

14. A lamp releasing key comprising hinged arcuate arms provided with an inwardly directed peg, and short finger grips for opening and closing said arms.

In testimony whereof I affix my signature. 80

THOMAS HENRY ALEXANDER BROWN.
